PREFABRICATED ARTIFICIAL TOOTH
RETAINING MEMBER

Irving Neustadter, Brooklyn, N. Y.

Application May 5, 1949; Serial No. 91,444

1 Claim. (Cl. 32—6)

2

This invention relates to dental restorations of the type commonly known as dental bridges or bridgework. A dental bridge consists of one or more artificial teeth mounted in a one-piece metal frame between two crowns or abutments which are made to fit over the adjacent natural teeth. In accordance with present practice, the making, forming, fitting and shaping of the one-piece metal frame is a task which requires much skill, takes much time and is expensive.

The object of this invention is to provide new means and a new method for constructing the metal frame between the abutments whereby the tedious and expensive work in making the usual one-piece frame may be eliminated. The invention is embodied in pre-fabricated artificial tooth retaining members which may be soldered directly to and between the abutments of the bridge so as to constitute and form a metal frame for the support and retention of artificial teeth molded about the members. By using such pre-fabricated members, the frame between the abutments is made quickly and much time and labor is saved.

A metal frame for a dental bridge made in accordance with this invention will consist of one or more separate individual pre-fabricated members soldered to each other and to the abutments between the latter. The members are new means for mounting the artificial teeth in the bridge. The securing of the pre-fabricated members to one another and to the abutments constitutes a new method for constructing the metal frame of the bridge. It is believed that the pre-fabricated members and the method of using them is entirely new in the art.

In the accompanying drawing illustrating the invention the latter is disclosed embodied in pre-fabricated tooth retaining members adapted for use with both posterior and anterior teeth in either an upper or a lower restoration. Two forms of such members are shown in the drawing. The selection of either form depends upon the local conditions and the nature of the restoration to be made.

Figs. 1, 2, 3 and 4 are, respectively, top, front, bottom and side views of one of the forms of pre-fabricated members embodying the invention.

Fig. 5 is a sectional view on the line 5—5 of Fig. 2.

Fig. 6 is a front and side view of an artificial tooth supported by and molded about a pre-fabricated member of the form shown in Figs. 1—6.

Fig. 7 is a view of a bridge consisting of two abutments and two members of the form shown in Figs. 1—6.

Figs. 8, 9, 10 and 11 are, respectively, top, front, bottom and side views of another form of pre-fabricated member embodying the invention.

Fig. 12 is a sectional view on the line 12—12 of Fig. 9.

Fig. 13 is a front and side view of an artificial tooth supported by and molded about a pre-fabricated member of the form shown in Figs. 8—12.

Fig. 14 is a view of a bridge consisting of two abutments and two members of the form shown in Figs. 8—13.

Fig. 15 is a view of a bridge as it appears mounted between two natural teeth and in which two artificial teeth are retained by two members of the two different forms shown in the preceding views.

Fig. 16 is a sectional view on the line 16—16 of Fig. 17 showing the retaining member formation of Figs. 8—12 applied to an anterior tooth.

Fig. 17 is a rear view of the anterior tooth shown in Fig. 16.

The pre-fabricated tooth retaining member 20 shown in Figs. 1—7 is of U-formation comprising 25 a transverse top occlusal portion 21 with two depending legs or mesial-distal members 22, 22. The occlusal surface is of whatever formation is required for a particular position in the mouth. The legs extend downwardly (upwardly in a lower restoration) from the occlusal portion and have slightly curved sides 23, 23 to conform to the curved sides of teeth. The legs are of less fore and aft dimension than the occlusal portion as shown in Figs. 5 and 6 and so that the legs are 30 invisible in the final installation. The occlusal portion is relatively thick and has its front and rear portions inclined angularly downward towards the legs as shown at 24, 24 to provide good abutting surfaces for the artificial tooth body and permit grinding, if any, without appreciably 35 diminishing the strength of the member. The legs 22 are likewise shaped with angularly inclined surfaces as at 50, 50 so that the molded tooth is held firmly against the inclined surfaces of 40 the member. A tooth reinforcing element 25, such as a pin, peg or wire, extends from the occlusal portion between the legs.

In constructing a metal bridge frame as shown in Fig. 7 the two abutments or crowns 26, 26 are 45 formed in the usual known manner. Thereafter one or more U-members 20 are placed between the abutments and soldered thereto and to one another. The members 20 constitute and form a frame for the retention of artificial teeth 55 between the abutments. The occlusal surfaces

21 of the members form continuations of the occlusal surfaces of the adjacent teeth. The members are prefabricated in graded sizes as articles of commerce. In order to construct the bridge, the technician merely selects members of the form most suitable for the work to be done, places them between the abutments and solder the parts together. The adjustment and fitting of the members for the work in hand is merely a matter of fitting them or shaping them according to the impression usually taken and is much less expensive and takes much less time than doing the work by the present method. Thereafter the artificial teeth are formed, molded and cast onto the metal bridge as is the present practice with one-piece frames.

Fig. 6 shows an artificial tooth 27 retained by an H-member 20. Only an edge 28 of the occlusal portion is visible from the front. The legs are invisible. Their curved sides 23 merge with and lie flush with the curved sides of the tooth. The latter is held strongly in the grip of the legs and by the reinforcing element 25. The member 20 provides an all metal biting surface 21 of the artificial tooth. However, this may not always be necessary or desirable, and the invention therefore includes another form of tooth retaining member such as shown in Figs. 8-14.

In these views the retaining member 30 is of H-formation comprising two sides or legs 31, 31 connected in the middle by a reinforcing shelf 32 having perforations 33. The legs are also connected below the shelf by a semi-circular rear band 34 having a thin bottom edge 35. The legs 31 are vertically of substantially triangular formation as seen in Fig. 9, the base of the triangle being at the top (bottom in an upper restoration). The portions 36 form exposed biting points or surfaces on each side of the tooth as seen in Fig. 13 where the right hand side view shows the surfaces of the portions 36 flush with the occlusal surface 37 of the tooth 38.

Fig. 14 shows a metal bridge in which the frame between the abutments 26 is formed of two H-members 30, 30. The placing, fitting, adjusting and grinding, if any, of the H-member 30 is done in the same manner as explained with reference to the U-member 20. The members 20 and 30 have the common feature of leg portions for gripping the artificial tooth with a reinforcing element between the legs. The U-formed member, Fig. 2, has the reinforcing element 25. The H-formed member, Fig. 9, has the reinforcing element 32 with apertures 33 through which the plastic substance of the tooth is forced, as will be understood.

Only an edge of the occlusal surface is seen when the U-member is used, whereas the H-member is entirely invisible from the front. The rear band 34 serves as an additional gripping member for the tooth and lies flush with the surface thereof. Either the U-member or the H-member is adapted for use with posterior teeth, either upper or lower.

Figs. 16 and 17 show an H-formed retaining member adapted for use with an anterior tooth,

upper or lower. The member 40 comprises the same parts as the member 30, compare Figs. 12 and 16. In Figs. 16 and 17 the two legs of the H are marked 41, 41. The connecting shelf is marked 42 and the band 43. The legs terminate short of the incisal edge 44 of the tooth 45. Otherwise the use of the member 40 in a bridge construction is the same as above described.

In manufacturing the tooth retaining members and offering them for sale to the industry, the members will be graded in a suitable number of sizes adapted to be used in the mouth to retain artificial teeth. The thicknesses and shapes of the members allow for such grinding as may be needed for fitting between sizes.

There may be bridge restorations in which both members 20 and 30 may be used. Fig. 15 illustrates a completed bridge comprising the abutments 26, a retaining member 20 and a retaining member 30, all being soldered together as indicated at 60. The natural teeth which bear the abutments are marked 61, 61. The two artificial teeth which are retained by the retaining members are marked 62, 63. The gum line is shown at 64. Fig. 15 illustrates that the occlusal surface 21 of member 20, and the surface portion 36 of member 30, form continuations of the occlusal surfaces of the adjacent teeth, respectively.

The embodiments of the invention illustrated in the drawing are shown very much enlarged. Depending upon the restoration to be made, the proper size and type of tooth retaining member will be selected and fitted between the abutments or other dental anchorage member and then soldered in place. The bridge will then be completed according to present practice.

I claim:

A pre-fabricated member for retaining artificial teeth in dental bridgework comprising an integrally preformed body of substantial U-shaped formation having a horizontally disposed transverse portion, the upper surface of which is formed to imitate the occlusal surface of a tooth, a smaller smooth under surface and inwardly sloping front and rear smooth surfaces joining said upper and under surfaces, vertically disposed mesial-distal side legs depending from said transverse portion at the sides thereof, said legs being thinner at the bottom than at the top and having outer curved surfaces and a supporting pin depending from the under surface of said transverse portion and spaced equidistantly between the said legs.
